C. H. GRINGS.
MOTOR VEHICLE SIGNALING DEVICE.
APPLICATION FILED JULY 10, 1920.

Patented Apr. 5, 1921.

UNITED STATES PATENT OFFICE.

CASPER HUGO GRINGS, OF WATERLOO, IOWA.

MOTOR-VEHICLE SIGNALING DEVICE.

1,373,808.

Specification of Letters Patent.

Patented Apr. 5, 1921.

Application filed July 10, 1920. Serial No. 395,304.

To all whom it may concern:

Be it known that I, CASPER HUGO GRINGS, a citizen of the United States of America, and a resident of Waterloo, Blackhawk county, Iowa, have invented certain new and useful Improvements in Motor-Vehicle Signaling Devices, of which the following is a specification.

My invention relates to improvements in motor-vehicle signaling devices, and the object of my improvement is to supply for such or any other vehicles a signaling apparatus of simple and inexpensive construction, easily mounted on or demounted from the vehicle, readily accessible for the chauffeur or driver for manual actuation, and which will not interfere with any use of the vehicle, nor emplacements of parts thereof.

I have accomplished the above object by the means which are hereinafter fully described and claimed, and which are illustrated in the accompanying drawings, in which Figure 1 is a perspective view of a part of a vehicle including a door thereof, showing my improved signaling device mounted on said door, with the semaphore retracted against the vehicle; Fig. 2 is an elevation on a larger scale of the signal actuating elements which are positioned without the vehicle, with parts sectioned or broken away; Fig. 3 is a horizontal section of a portion of the vehicle door or part on which the device is removably mounted, showing the coöperating actuating elements partly in plan and partly in section, with parts broken away; Fig. 4 is an elevation of the housing for the outer actuating elements of the device, and Fig. 5 is a cross section of the hollow bolt and contained rock-shaft, taken through the L-part of the slot in said bolt.

In said drawings, like numerals of reference denote like parts throughout the several figures.

My improved signaling apparatus may be removably mounted upon any fixed or movable structure of a vehicle, but as shown herein, it is mounted upon the door 18 of the vehicle-body 36, where its operating handle 11 may be within convenient access to the operator. Before so mounting the device, it is merely necessary to make a transverse hole 19 in the door 18 to receive a headed hollow bolt 5, the bolt being exteriorly threaded throughout most of its

length, so that it may be used on doors or other supporting-means of different thicknesses. As shown in Fig. 3, a hollow housing 21 is mounted upon the outside of the door and has an opening to permit the passage of a bolt 5 therethrough whose head is clamped thereagainst by the action of a nut 17 on the opposite end of the bolt which compresses a large intermediate washer 16 against the opposite side of the door. Said bolt has a longitudinal slot 8 terminating toward the inner face of the door in a short angularly directed part 9.

The numeral 1 denotes a shaft which is mounted within the hollow of said bolt to rock therein, and also for longitudinal reciprocal movements therein, and projects at both ends from the bolt. The end of said shaft which extends into the housing 21 has a relatively large discoidal head 2 provided with a short coaxial arcuate slot 3. A pin 4 extends outwardly fixedly from the inner wall of the casing 21 underlying the door, with its outer end extending loosely into said slot 3. A coiled compression spring 20 is mounted on the pin 4 and is engaged between said wall and the opposite face of the discoidal head 2, and thrusts outwardly evenly thereon. The inner end of the shaft 1 is diminished and squared at 10 to receive adjustably the bearing end 12 of a crank handle 11 supplied with a terminal 5 or fingerhold 15. This permits the handle to be mounted adjustably in any one of four positions on said shaft, as convenient or desired. The end of the shaft is provided with a still more diminished and threaded extremity 14 to receive the nut 13.

Within the housing 21 is fixed vertically spaced bracket members 23 and 27 with their integral connecting plate 26, and the said members are orificed in vertical alignment to receive the vertical rock-shaft 25 having on its upper end an angularly bent crank or contact member 24. This crank extends into the path of movement inwardly of the discoidal head 2. At a distance below the lower member 27, said shaft 25 is bent at a right angle at 32, the latter part projecting outwardly through a horizontal slot 22 in said housing. This part 32 may form a short terminally threaded section of a two-part semaphore-arm 33, the latter also threaded and removably connected to the part 32 by a sleeve-nut 34. This permits

the arm 33 to be demounted when desired. On the outer end of the arm 33 is mounted a discoidal semaphore body 35.

The numeral 28 denotes a coiled spring 5 mounted on a shaft 25 below the bracket member 27, and has one terminal 30 secured to a tongue 29 cut out from the back wall of said housing. The other terminal 31 of said spring is connected to the angularly 10 directed part 32 and tends to yieldingly move the semaphore toward the vehicle. As shown in said Fig. 3, when the semaphore is in this retracted position, its angularly directed crank-arm 24 is, by the 15 action of said spring, kept in terminal contact with the abutting face of the discoidal head 2 of the shaft 1.

When the crank arm 11 is pulled inwardly, it not only causes the head 2 to compress 20 the spring 20, but said head also engagingly rocks the crank-arm 24 inwardly, thus rocking horizontally outwardly the arm 33 and the semaphore while placing the other spring 28 also under tension. When the 25 crank arm 11 is released, the reaction of said spring will simultaneously thrust said shaft outwardly, but will also rock the arm 33 inwardly to its retracted position. The numeral 7 denotes a short pin fixed on 30 the shaft 1 to extend into the longitudinal slot 8 in the bolt 5 terminating just short of the roots of the threads thereon to not interfere with the adjustable seating of the nut 17 upon the bolt. The pin 7 is so positioned on the shaft 1 that when the latter has been reciprocated inwardly to its limit 35 of movement in that direction, said pin will be opposite the lateral slot 9, so that if the arm 11 is rocked in one direction a short 40 distance, said pin will become engaged with the walls of the slot 9 to releasably lock the shaft to the bolt, thus holding the semaphore 35 in its outward or signaling position. Reversely rocking the arm 11 releases 45 the pin 7 so that said springs will again extend the shaft 1 and also retract the semaphore. The slot 3 in the head 2 permits this rocking displacement of the head 2 relative to the fixed pin 4.

50 It will be seen that this device is very simple, inexpensive, and easily mounted or demounted.

Slight variations in the elements of the device, their positions, arrangements, dimensions, or otherwise, are nevertheless covered by the scope of this invention.

Having described my invention, what I claim as new, and desire to secure by Letters Patent, is:

60 1. In a device of the character described, a shaft having a discoidal head, said shaft being mounted to rock on and for longitudinal reciprocation relative to a vehicle, a semaphore mounted pivotally on said vehicle to rock horizontally and having a crank-

arm positioned in the path of reciprocatory movement and in contact with the said discoidal head, yieldable resilient means operable upon said discoidal head in one direction, and other yieldable resilient means operable upon said semaphore to yieldingly retain it in contact with said discoidal head. 70

2. In a device of the character described, a shaft having a discoidal head, said shaft being mounted to rock on and for longitudinal reciprocation relative to a vehicle, a semaphore mounted pivotally on said vehicle to rock horizontally and having a crank-arm positioned in the path of reciprocatory movement and in contact with the said discoidal head, yieldable resilient means operable upon said discoidal head in one direction, other yieldable resilient means operable upon said semaphore to yieldingly retain it in contact with said discoidal head, 80 and means for limiting the scope of rocking movements of said shaft. 85

3. In a device of the character described, a shaft having a discoidal head, said shaft being mounted to rock on and for longitudinal reciprocation relative to a vehicle, a semaphore mounted pivotally on said vehicle to rock horizontally and having a crank-arm positioned in the path of reciprocatory movement and in contact with the said discoidal head, yieldable resilient means operable upon said discoidal head in one direction, other yieldable resilient means operable upon said semaphore to yieldingly retain it in contact with said discoidal head, 90 and means for releasably locking said shaft in a certain position of reciprocation. 95

4. In a device of the character described, a shaft having a discoidal head, said shaft being mounted to rock on and for longitudinal reciprocation relative to a vehicle, a semaphore mounted pivotally on said vehicle to rock horizontally and having a crank-arm positioned in the path of reciprocatory movement and in contact with the said discoidal head, yieldable resilient means operable upon said discoidal head in one direction, other yieldable resilient means operable upon said semaphore to yieldingly retain it in contact with said discoidal head, 105 and means for limiting the scope of rocking movements of said shaft, and means for releasably locking said shaft in a certain position of reciprocation. 110

5. In a device of the character described, 120 a shaft having a discoidal head, said shaft being mounted to rock on and for longitudinal reciprocation relative to a vehicle, a semaphore mounted pivotally on said vehicle to rock horizontally and having a crank-arm positioned in the path of reciprocatory movement and in contact with the said discoidal head, yieldable resilient means operable upon said discoidal head in one direction, other yieldable resilient means oper- 125 able upon said semaphore to yieldingly retain it in contact with said discoidal head, 130 and means for limiting the scope of rocking movements of said shaft, and means for releasably locking said shaft in a certain position of reciprocation.

able upon said semaphore to yieldingly retain it in contact with said discoidal head, and a hand-hold removably adjustably secured upon the inner end of said reciprocating shaft.

6. In a device of the character described, a longitudinally hollowed exteriorly-threaded bolt secured removably adjustably in a transverse opening in a vehicle supporting member, a longitudinally reciprocatory rock-shaft secured removably in the hollow of said bolt to project at both ends thereof, an operating crank-handle adjustably removably secured upon the inner end of said shaft, 10 said shaft having a discoidal head upon its outer end provided with a coaxial arcuate slot, a fixed pin on said supporting member

extending into said slot, a coiled compression spring mounted on said pin and bearing against said discoidal head, said bolt 20 having an L-shaped slot and said shaft having a stud extending into said slot, a semaphore arm mounted pivotally on said supporting member to rock to and from it horizontally and having a crank-arm extending 25 into the path of movement of and contacting the inner surface of said discoidal head, and yieldable resilient means connected to said semaphore adapted to yieldingly retain it in a retracted position abutting upon said 30 vehicle.

Signed at Waterloo, Iowa, this 1st day of July, 1920.

CASPER HUGO GRINGS.
